UNITED STATES PATENT OFFICE.

JOHN TOMBOW, OF MASSILLON, OHIO, ASSIGNOR OF ONE-HALF TO VICTOR KERN, OF SAME PLACE.

WASHING-MACHINE.

SPECIFICATION forming part of Letters Patent No. 301,075, dated June 24, 1884.

Application filed June 30, 1883. (No model.)

To all whom it may concern:

Be it known that I, JOHN TOMBOW, a citizen of the United States, residing at Massillon, in the county of Stark and State of Ohio, 5 have invented certain new and useful Improvements in Motors for Washing-Machines, &c.; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to improvements in washing-machines; and it consists in the construction of the body and the operating mechanism, substantially as hereinafter described and claimed.

20 In the drawings, Figure 1 is a plan, and Fig. 2 is a vertical section, of a machine constructed according to my invention. Fig. 3 is a detail view of one of the arms of the bifurcated operating-lever. Fig. 4 shows in detail the joint 25 of the lid and body, as will be described; and Fig. 5 is a detail view of the hook.

The body A is made in usual tub form, and is 30 preferably mounted on legs A', as shown. On one side the staves of the tub are projected above the main portion, to provide the upward extension A². At the side edges of this extension, in line with the top of the tub, I form notches a a, and on the inner side of the said extension, in line with the top of the tub, form a groove, a'.

35 The lid B is made to conform to the shape of the top of the body A, and is cut away on one side to form the bead b, made to fit into the groove a', and of a length equal to the said groove, and the said lid B is provided on the side opposite the bead with a suitable bar to be engaged by the hook on the tub A. Thus, in 40 order to secure the lid on the tub, it is only necessary to slip the bead or edge b into the groove a', when the edges or shoulders b' of the lid on opposite sides of the bead will come 45 within the notches a, and the hook being caught over its engaging bar, the lid will be firmly secured on the body or tub. An arch, C, is mounted on the lid in a diametrical line drawn 50 through about the middle of the bead b, and

its end opposite the said bead is extended to form the bar c, which is engaged by the hook c' on the tub in the operation of securing the lid in place. In the crown of this arch I form a bearing for the shaft of the agitating-frame, 55 hereinafter described. On the lid under the bearing c² in the arch I fix a plate, D, through which, in a vertical line with the bearing c², I form the bearing d. The shaft E has a suitable agitating device, e, secured on its lower 60 end, and is constructed with the journal e' next the said agitator, which journal rests in the bearing d, and the journal e², which rests in the bearing c², as shown. On the shaft between these two journals I key the drum F, 65 which is made shorter than the space between the arch and the lid, and the journals e' e² are made of a sufficient length to permit the vertical movement of the frame e, as indicated in dotted lines, Fig. 2, whereby said frame 70 adjusts itself to the position of the substance being agitated.

On the lid near the bar c, I mount the stud or standard G, which is provided near its upper end with an annular flange or rib, g, 75 above which is formed the bearing g' for the operating-lever H. This lever is provided with a suitable opening, h, slipped over the bearing g', as shown, and it has its rear end extended to provide the handle h', and its forward end is bifurcated, to provide the arms h² h³, preferably made of spring metal, and of a length about half the diameter of the tube A, 80 as shown. The outer sides of these arms h² h³ are formed with grooves h⁴, and at the rear end of these grooves openings h⁵ are formed through the arms, the one in arm h³ being threaded to receive the screw h⁶, for the purpose hereinafter described. A stout string, I, (catgut preferred,) is secured within the hole h⁵ in the arm h³, and wrapped several times 85 around the drum F, and is extended to the opening h⁵ in arm h³, and drawn taut and secured by the screw h⁶. The string is then sprung over the end of arm h³ into the groove h⁴, and is thereby given additional tension. By the forward-and-back motion given the 90 agitator, currents of steam and water are formed and reversed in quick succession within the tub, and the clothing is rapidly and 95 100

thoroughly cleansed. The lever is moved from side to side, and the drum and shaft are revolved, giving the agitator the desired motion and a high rate of speed.

5 My machine, it will be understood, is equally useful in churns and washing-machines, and I do not desire to be limited to its application to either.

Having thus described my invention, what I 10 claim, and desire to secure by Letters Patent, is—

1. In a churn or washing-machine, the combination of the body or reservoir A, having a vertical projecting arm, A², extended above the rim thereof, and provided with a groove or chine, a', cut on its inner face in line with the said rim, and transverse notches a, cut from the ends of the chine a' outward across the ends of the arm A², to the outer side thereof, the lid B, having its rim or periphery extended over the upper edge and flush with the outer side of the body A, and having a portion of one side cut away, whereby the edge or bead b and shoulders b' are formed, and adapted to fit snugly into the chine a' and transverse notches a, and a retaining hook or clasp arranged on the side of the lid or box opposite to the arm A, substantially as and for the purposes set forth.

2. The combination, in a washing-machine,

of the tub A, having upward extension A², formed with inner groove, a', and notches or slots a, the lid B, having a central bearing for the agitator-shaft, and cut away on one side, providing the bead b, fitted to groove a', and 35 notches a, the hook c', pivoted at one end to the tub on the side opposite the extension A², bar C, secured on the lid in a diametrical line drawn through center of bead b, and having its end c opposite said bead projected 40 in position to be engaged by hook c', the agitator-shaft journaled in bearings formed in the lid and the bar C, and means for operating the said shaft, substantially as specified.

3. The combination of the box or body, the 45 agitator-shaft, the pivoted operating-lever having its arms h² h³ made of spring material, and provided on their outer sides near their ends with grooves h⁴, and the cord I, wrapped around the agitator-shaft and having its ends 50 secured to the arms h² h³ at a point back from the ends thereof, and sprung into the grooves h⁴, substantially as set forth.

In testimony whereof I affix my signature in presence of two witnesses.

JOHN TOMBOW.

Witnesses:

ISAAC ULMAN,
J. J. MALLS.
